United States Patent Office.

LEVERETT BRADLEY, OF JERSEY CITY, NEW JERSEY.

Letters Patent No. 95,310, dated September 28, 1869.

IMPROVEMENT IN ELECTRIC CLOCKS.

The Schedule referred to in these Letters Patent and making part of the same.

To all whom it may concern:

Be it known that I, LEVERETT BRADLEY, of Jersey City, in the county of Hudson, and State of New Jersey, have invented a new and useful Improvement in Electric Clocks, of which the following is a full, clear, and exact description, reference being had to the accompanying drawing, forming part of this specification, and which represents an interior view, parallel to their dials, of a governing-clock, operated by a spring or weight, and secondary clock, under control or action by electricity of the governing-clock.

My invention has for its object the establishing and maintaining of an isochronous working of any number of clocks, at greater or less distances apart, from a governing-clock, operated by a spring or weight, through the agency of electro-magnets between which and the governing-clock, the circuit is broken and established at regular intervals, by the action of the pendulum of the latter clock as a controlling power or device.

In thus working a series of clocks, great irregularity and uncertainty have heretofore prevailed, owing to certain imperfections which have existed in closing the circuit, by the action of the pendulum of the governing-clock toward or at the close of each of its vibrations, when the momentum of the pendulum, hung to vibrate in a vertical plane, is checked or retarded, as it were, which, occurring at the very period its power is required to close the circuit, coupled with a certain irregular or tremulous action of the circuit-closing device or devices, as superinduced by the electric current, causes feebleness or want of uniformity, that fails to produce a regular isochronous action.

This difficulty I entirely obviate by the combination, with a rotating circuit-closer, operated by the governing-clock, of a conical pendulum, which, having a revolving, as contradistinguished from a straight or vibrating action, retains its power or momentum to close the circuit, and, operating in connection with the rotating circuit-closer, feels or communicates no shock or check, but effects the closing of the circuit in a firm and positive manner, free from any interruption by tremulous action.

Also, the invention consists in a certain combination of pawls, for insuring regularity in the movement of the secondary clock or clocks, and to prevent any over-leaping, as well as back-action of the driving-wheel or wheels, worked by the swinging armature or armatures of said clock or clocks, and thereby further contributing to establish a perfect isochronous action.

Referring to the accompanying drawing—

A represents a clock, which is the governing one, and which, so far as its works generally are concerned, may be of ordinary construction.

Instead, however, of a pendulum being used that

vibrates in a vertical plane, I use what is known as a conical pendulum, B, having a revolving swing or action, and which may derive its motion, for the performance of its regular function, from a vertical screw, a, through the agency of a wheel, b, in suitable gear with the spring-operated barrel c of the clock.

On the rotating arbor C of this wheel are arranged one or more radial circuit-closers, D, each of which dips into or comes in contact with, as it passes, a globule of mercury, d, contained in a wooden or insulating-trough, E, and which has one of the wires e of a battery in contact with it, while the other wire f, which connects with the opposite pole of the battery, is coiled, to form an electro-magnet or magnets, F, and is in connection, at its one end, with the metallic frame-work of the clock A.

Thus, it will be seen that as the circuit-closer D, under the control of the pendulum B, touches at regular intervals, once during each rotation of it, the globule of mercury d, it closes the circuit, and, through the electro-magnets F, serves to operate in the one or working-direction, to a secondary clock, G, a soft-iron armature, H, that swings on a centre at g.

This secondary clock G may, of course, be situated at any desired distance from the primary or governing-clock A, that may have its arbor C provided, or extended, and provided with any number of circuit-closers D, preferably arranged to come in contact in consecutive order, so as to distribute circuit-closing strain or effort on the primary clock, with globules of mercury, contained in suitable insulating-troughs, for operating in like manner, through similar or suitable battery-connections and electro-magnets, any number of secondary clocks situated at any desired distance from the single governing-clock, so as to maintain an isochronous action of a multiplicity of clocks.

I do not restrict myself to using mercury as the metallic conductor for closing the circuit, as it is quite practicable to employ a positive or frictional contact of the circuit-closer with a properly-constructed point to the wire that establishes or connects with the one pole of the battery, by reason of the combination of the rotating circuit-closer with the revolving or conical pendulum, which retains its power or momentum in a uniform manner throughout its entire swing or action, and has a force, that, in connection with the revolving motion of the circuit-closer, secures it from being interfered with or affected by the temporary work of closing the circuit.

The armature H of the secondary clock G is drawn back, after the circuit is broken, by a spring, h, against an adjustable stop, i.

This armature is made to operate the fingers on the dial of the clock (each time the circuit is closed) the necessary distance to secure an isochronous action.

with the primary or governing-clock, by means of a feeding-pawl, I, pivoted to an arm, k, of the armature, and star-wheel J, that is driven by said pawl.

K is a stop-pawl to the wheel J, to restrain it from working back in or by the return-stroke of the feeding-pawl I.

Connected with this stop-pawl K, by a spring, m, is another locking or check-pawl, L, pivoted as at n, and under control of an adjustable stop, r, attached to the arm k of the armature, in order that when said armature is drawn forward by the electro-magnets, to perform its feeding-stroke to the wheel J, the pawl L is worked out of gear with said wheel, so as not to interfere with the motion given to the latter by the feeding-pawl I; but as the latter commences its back-stroke, said pawl L, by the action of the spring m, shoots into lock with the wheel, and prevents it from overleaping its feed; also, in connection with the stop-pawl K, establishes a lock of the wheel I, and restrains it, or the

fingers operated by it, from being worked in either way, either accidentally or otherwise.

This arrangement or combination of pawls materially contributes to secure a perfect isochronous action, and prevents tampering.

What is here claimed, and desired to be secured by Letters Patent, is—

1. The combination of one or more rotating circuit-closers D with the conical pendulum B of the primary or governing-clock A, substantially as specified.

2. The combination, with the wheel J and armature H, carrying the operating-pawl I, of the pawls L K and spring m, essentially as and for the purpose or purposes herein set forth.

L. BRADLEY.
